BIRGER TORVALD ANDREN, OF MILWAUKEE, WISCONSIN, ASSIGNOR TO A. C. SMITH CORPORATION, OF MILWAUKEE, WISCONSIN, A CORPORATION OF NEW YORK.

TORSION-RESISTING CROSS BAR FOR AUTOMOBILE FRAMES.

Application filed June 28, 1926. Serial No. 119,013.

The invention relates to an improved construction of torsion resisting cross bars for automobile frames, in which the attaching gussets are formed integrally therewith.

It resides generally in a cross bar of polygonal cross section formed from a channel or U-shaped member, and a rectangular plate permanently secured to the free edges of the sides of the channel member to complete the integral tubular formation. The margins of the said plate adjacent the ends of the channel member constitute the integral gussets whereby the cross bar may be attached at its ends to the side bars of an automobile frame. The structure may vary on its cross sectional lines in the length of the bar, to meet the specifications of the construction in which the cross bar is employed. The channel member in any of the forms of the bar, is drawn from a strip of sheet metal of uniform width, following which procedure the usual operation to produce a contoured blank is eliminated, and the whole amount of metal in the rectangular strip is thus incorporated in the cross bar without waste.

In one form of the invention, the cross bar comprises as one of its elements an arch forming member with a flat top varying in width, and with depending sides also varying in width, the latter being disposed perpendicularly with relation to the flat top. The top of the arch forming member is wide at its middle and narrow at its ends. The depending sides are deepest at the ends of the cross bar where the arch is narrow, and have their least depth at the center of the cross bar where the arch is widest, viewing the said bar as positioned in the frame of which it constitutes an element. In any cross section, the arch forming member has the shape of an inverted U-channel or rectangular structure open at its bottom side, and the circumference of the said member is the same on any cross sectional line. The narrowed formation at the ends of the arch member subserves a purpose which later will be described.

The structure is completed by the addition to the inverted channel member forming the arch, of a bottom plate formed of a metal strip having a width approximating, or slightly in excess of that of the arch forming member at the widest part of the latter,

which plate closes the downwardly opening channel in the arch forming member, such bottom plate being bowed upwardly to conform to the curvature of the lower edges of the depending sides of the arch forming member. The projecting ends of the bottom plate are returned over the ends of the channel member which they abut, and again over the top of the arch forming member for a short distance. Such bottom plate and the lapped ends are welded to the lower edges and the ends of the depending sides of the arch forming member preferably along all meeting lines, and the extreme ends of the plate to the top of the arch forming member, so as to form an integral and inelastic structure.

In my invention, the margins of the bottom plate which extend laterally of the cross bar, are made thus to embrace the narrowed ends of the channel member, and are utilized as integrally formed gussets through which the ends of the cross bar are attached to the side bars to constitute the frame as a fixed structure. The construction is such that all of the usual separate gussets are dispensed with, and the number of elements entering into the construction of the frame is thereby reduced.

The novel features of the invention will now be described in detail, and then pointed out in the claims appended to this specification.

In the accompanying drawing:

Figure 1 is a plan view of an improved cross bar of arch formation constructed in accordance with my invention, the view being broken out at parts for the sake of clearness, and showing the manner of attaching the ends of the cross bar to the side bars of an automobile frame, by means of the gussets formed integrally with the cross bar.

Fig. 2 is a view in elevation of the cross bar, with the side bars in section.

Fig. 3 is a transverse vertical section of the cross bar at the crown of the arch, looking in the direction of the arrows 3-3, Fig. 2.

Fig. 4 is a similar view of one end of the cross bar on the line 4-4, Fig. 2.

Fig. 5 is a like view on the line 5-5, 105 Fig. 2.

Fig. 6 is a horizontal sectional view showing one end of the cross bar at the point of

its attachment to the side bar, and showing a slight modification in the contour of the bottom plate of the cross bar which otherwise is the same as that previously shown.

Fig. 7 is a view similar to Fig. 4, taken on the line 6—6, Fig. 6, and showing the modified construction.

In making my improved cross bar, I take a rectangular strip of sheet metal of suitable width and length and by the action of a metal drawing press convert the same into a longitudinally channelled member of U-shape in any cross section. The channel is narrow and deep at its ends and wide and shallow at its middle, as will be apparent from Fig. 1, the web or flat bottom of the channel tapering horizontally from its central section toward its ends and the sides thereof vertically from the center section to the end sections to produce the depth described, as in Fig. 2, through an intermediate section in which the width of the web and the sides are equal, so as to form an approximately square cross section. These different formations of the arch forming member are indicated in Figs. 3, 4 and 5, respectively. In Fig. 3 the numeral 11 indicates the widened web or bottom of the channel and 11' and 11'' the shallow sides thereof. In Fig. 4 the numeral 12 indicates the narrow portion of the web or bottom and 12' and 12'' the widened sides thereof. In Fig. 5 the web or bottom 13 and the sides 13' and 13'' are substantially equal in length, so as to form an intermediate square cross section through which the central construction illustrated in Fig. 3 merges into that shown in Fig. 4.

A rectangular plate 14, having a width only a little in excess of that of the greatest width of the channelled arch forming member, and a length which will enable its ends to project beyond those of the said member, is bent so as to conform to the curvature of the lower edges of the sides of the arch forming member, the plate 14 being welded to the said edges in the outer angle formed at their meeting lines, throughout the length of the latter, as indicated at 14'. The ends of the strip or plate 14 are upturned as at 15 and 16, so as to abut the ends of the arch forming member and are welded thereto as at 15' and 16', on lines which are continuous of the curved welding lines 14' which unite the parts. The upstanding ends of plate 14 are then lapped over as at 17 and 18, so as to lie upon the top of the arch forming member at the ends thereof. The laps 17 and 18 may be welded to the top of the arch forming member, as at 17' and 18', if found desirable.

By reason of the uniform width of plate 14, the margins 19 and 20 lying outside of the arch forming member at the narrowed ends of the latter, are utilized as gussets

which are integrally formed with the cross bar, so that the ends of the cross bar may be attached to the side bars 21 and 22, as shown in the drawing, whereby the elements of the frame may be assembled and connected with greater facility, and the extra work of preparing and positioning separate gussets is eliminated.

Figs. 6 and 7 show a slight modification in the structure, in that portions of the margins 19 and 20 of the plate 14 are cut away as indicated at 23 in Fig. 6, so as to follow the lateral displacement of the sides of the arch forming member, and the lower edges of the sides of such member are turned outwardly as at 24, in Fig. 7, so as to bring the laterally extending edges 23 and 24 into alignment to permit the fusing and welding of the edges together as indicated at 25. This modification involves an additional blanking operation, but offers advantageous welding, however. It has a further advantage in that by the removal of excess material it lightens the weight of the cross bar in a small degree.

The box-like tubular structure in which the present invention is embodied in its different forms offers a torsional resistance to the stresses imposed on the frame, and maintains the latter against distortion by load or unfavorable road conditions.

In the specific form in which the invention is illustrated, the arch formation is employed to provide a clearance for the motor mechanism in certain types of automobiles, but the construction shown may be varied, and in some constructions the dimensions of width and height of the cross bar may be uniform, without departing from the spirit of my invention. Any change in proportions, so long as the essential features of the gusset formations upon the ends of the cross bar are preserved, will be within the scope of the claims.

Having thus described my invention, what I claim and desire to secure by Letters Patent of the United States, is:

1. In an automobile frame, a torsion resisting cross bar comprising a channel member and a plate permanently secured to the free edges of the sides of said channel member to cover the channel and complete a rigid tubular structure, the said plate extending laterally of the ends of the channel member and forming integral gussets at the ends of the cross bar, whereby the latter may be attached to the side bars of the frame.

2. A torsion resisting cross bar for automobile frames, such bar comprising an inverted channel member and a plate permanently secured to the free edges of the depending sides of said channel member to close the channel and form a rigid tubular structure, the said plate extending laterally of the ends of the channel member and form-

ing integral gussets at the ends of the cross bar, whereby the latter may be attached to the side bars of the frame.

3. A torsion resisting cross bar for automobile frames, such bar comprising a channel member narrow at its ends and a plate secured to the free edges of the sides of said channel member to close the channel and form a rigid tubular structure, the said plate extending laterally of the narrowed ends of the channel member and forming integral gussets at the ends of the cross bar, whereby the latter may be attached to the side bars of the frame.

15 4. A torsion resisting cross bar for automobile frames, such bar comprising a channel member wide at its middle and narrow at its ends and a plate secured to the free edges of the sides of said channel member to close the channel and form a rigid tubular structure, the said plate extending laterally of the narrowed ends of the channel member and forming integral gussets at the ends of the cross bar, whereby the latter may be attached to the side bars of the frame.

25 5. A torsion resisting cross bar for automobile frames, comprising a channel member and a plate permanently secured to the free edges of the sides of said channel member to close the channel and form a rigid tubular structure, the said plate extending laterally of and embracing the ends of the channel member to form gussets integral with the cross bar, whereby the latter may be attached to the side bars of the frame.

40 6. A torsion resisting cross bar for automobile frames, comprising a channel member and a plate permanently secured to the free edges of the sides of said channel member to close the channel and form a rigid tubular structure, the said plate extending laterally of the ends of the channel member and the projecting ends of the said plate being returned over the ends of the channel member and secured thereto to form gussets integral with the cross bar, whereby the latter may be attached to the side bars of the frame.

50 7. A torsion resisting cross bar for automobile frames, such bar comprising an inverted channel member having a flat top and depending sides and narrow at its ends, and a plate secured to the lower edges of the depending sides to close the channel, the said plate extending laterally of the narrowed ends of the channel member, whereby integral gussets are provided for attaching the cross bar to the side bars of the frame.

60 8. A torsion resisting cross bar for automobile frames, such bar comprising an inverted channel member having a flat top widened at its middle and narrowed at its ends and depending sides, and a plate secured to the lower edges of the said sides and attached thereto to close the channel, the

said plate extending laterally of the narrowed ends of the channel member, whereby integral gussets are provided for attaching the cross bar to the side bars of the frame.

9. A torsion resisting cross bar for automobile frames, such bar comprising an inverted channel member having a flat top widened at its middle and narrowed at its ends and depending sides, and a plate having a width approximating that of the widened part of the cross bar secured to the lower edges of the said sides to close the channel, the end margins of the said plate extending laterally of the narrowed ends of the channel member, whereby integral gussets are provided for attaching the cross bar to the side bars of the frame.

10. A torsion resisting cross bar for automobile frames, such bar comprising an inverted U-shaped channel member having a flat top wide at its middle and narrow at its ends, with depending sides deeper at their ends than at their middle to form an arch, a bottom plate bowed to conform to the curvature of the lower edges of the said sides and secured thereto to close the channel, the said plate extending laterally with relation to the said narrow ends and forming integral gussets for attaching the cross bar to the side bars of the frame.

15 11. A torsion resisting cross bar for automobile frames, such bar comprising an inverted U-shaped channel member having a flat top wide at its middle and narrow at its ends, with depending sides deeper at their ends than at their middle to form an arch, a bottom plate bowed to conform to the curvature of the lower edges of the said sides and secured thereto to close the channel, the said plate extending laterally of the said narrow ends and upturned to abut the ends of the said sides to form integral gussets for attaching the cross bar to the side bars of the frame.

20 12. A torsion resisting cross bar for automobile frames, such bar comprising an inverted U-shaped channel member having a flat top wide at its middle and narrow at its ends, with depending sides deeper at their ends than at their middle to form an arch, a bottom plate bowed to conform to the curvature of the lower edges of the said sides and secured thereto to close the channel, the ends of the said plate extending beyond the ends of the channel member being returned to embrace the narrow ends of the channel member to which they are secured, to form integral gussets whereby the cross bar may be attached to the side bars of the frame.

25 13. A torsion resisting cross bar for automobile frames, such bar comprising an inverted U-shaped channel member having a flat top wide at its middle and narrow at its ends, with depending sides deeper at

their ends than at their middle to form an arch, a bottom plate having a width approximating that of the wider part of the channel member and bowed to conform to the curvature of the lower edges of the said sides and secured thereto to close the channel, the ends of the said plate being returned around and over the narrow ends of the channel member and secured thereto to form integral gussets for attaching the cross bar to the side bars of the frame.

14. A torsion resisting cross bar for automobile frames, comprising a channel member of given width and length and a plate 15 of greater width and length permanently se-

cured intermediately to the free edges of the sides of said channel member to close the channel and form a rigid tubular structure, the projecting ends of the said plate being returned over the ends of the channel member and secured thereto, and portions of the plate extending laterally of the ends of the channel member forming integral gussets upon the cross bar, whereby the latter may be attached to the side bars of the frame. 20

In testimony whereof, I have signed my name at Milwaukee, this 11th day of June, 1926.

B. T. ANDREN.
